Attorney

UNITED STATES PATENT OFFICE.

MICHAEL JOSEPH McANDREW, OF CLARKSBURG, WEST VIRGINIA.

RAIL TIE.

Application filed February 25, 1927. Serial No. 170,913.

The present invention relates to an improved rail tie, which is especially, although not necessarily designed for use in the construction of steel mine tracks, such as are employed in coal mines and other industrial plants.

The main purpose of the invention is to provide a simple and inexpensive all metal tie, such as will facilitate assembling and laying of tracks, and which is such as to hold the tracks in proper alignment under all conditions.

The invention is characterized by many important features. For instance, it is made of one solid piece of steel, has a double strength wedge backing, embodies no clips, nuts, bolts, rivets, or other fastening catches to work loose and includes no spikes or splice bars such as are ordinarily used. The invention is advantageous, in that the workman needs nothing except regular tools to lay the track. The invention permits a jumper or extension rail to be used, and keeps the track up to the face. It maintains the tracks in true gage, saves much head room, is very easy to handle, and the track can be laid quickly. It can be used time and time again.

The added wedge strength, and no clips, nuts and bolts or other fastenings increases the life of the ties in comparison to other steel ties of the same character. Inasmuch as the device is in one piece, no extra parts are required.

The invention will reduce operating and maintenance cost and is advantageous in that it can be employed with any sized steel rail, ranging from twelve to thirty pounds.

Other features and advantages accompany the invention, and these will become apparent from the following detailed description and drawings:

In the drawings;

Figure 1 is a top plan view of a railway track, showing the improved ties associated therewith.

Figure 2 is a cross section through the track, showing the association of the clamping means more in detail.

Figure 3 is a fragmentary detail sectional and elevational view, showing how a jumper or extension rail can be used, in order to keep the track up to the face.

In carrying out the invention I employ a

one piece solid steel body 1, which is channel shaped in cross section. The opposite ends thereof are directed upwardly, as at 2, to form hooks, the bills of which terminate on a plane substantially even with the head 3 of the rail. These hooks are disposed in spaced relation to the web and base flange of the rail, and assume the approximate position shown in Figure 2. The curvature of the hook, in each instance is such as to accommodate the curved side 4 of a driven retaining wedge 5. The opposite face of the wedge, however, is flat, in order to bear against the flat surface of the web of the rail. As a matter of fact, the wedge is shaped throughout to conform to the surfaces of the tie and the rail. It will be noticed that an extension is formed to provide the bill of the hook, the extension starting at about the point 6, being bent outwardly and around to the curvature of the hook and then being directed inwardly as at 7, and terminating in a smaller base flange engaging hook 8. This extension is of a yieldable nature, and it is obvious that the tighter the wedge is driven the firmer the clamping action of the hook 8.

By referring to Figure 3, it will be observed that the extension rail, in each instance, is clearly interposed between the web of the main rail and the hooked end of the special tie, the same being held in place by a relatively small wedge which is driven in between the base flange of the complementary rail and the extension strap of the tie. It is of course quite common to employ these supplemental extension rails in practice, and the only change required when used with the improved tie is the employment of smaller wedges.

The invention is of such simple nature that the construction and method of application and use is quite clear. For this reason, a more lengthy description is believed to be unnecessary.

Minor changes, in the size, shape and proportions, coming within the scope of the invention claimed, may be resorted to, if desired.

I claim:

1. A rail tie of the class described comprising a body having hooks formed at its opposite ends, together with yieldable extensions terminating in base flange engaging

hooks and shaped to conform to the interior of the first named hook and to underlie the base flange of the rail.

2. In a structure of the class described, in combination, a track including spaced parallel rails having heads, base flanges, and connecting webs, a one piece tie connector extending transversely beneath the base flanges of the rails, the tie having upstanding hooks formed at its opposite ends, the bills of these hooks terminating on a plane substantially even with the heads of the rails, said tie including end extensions bent downwardly, curved outwardly, then directed to underlie the base flange of the rails and terminating in hooks to engage the opposite edge of the base flanges, and retaining wedges interposed between the web of the rail and the curved portion of said ex-

tensions, the wedges being of a cross sectional shape to conform to the surfaces which they contact.

3. As a new product of manufacture, a rail tie of the class described comprising a one piece metal body of elongated form and of channel shaped cross section, said body terminating at each end in an upwardly curved hook, an extension strap extending from the extremity of each hook, being bent downwardly upon itself, then inwardly to conform to the curvature of the inner side of said hook, and the portion of the strap being bent inwardly to overlie the top of the body portion and then terminating in a base flange engaging hook.

In testimony whereof I affix my signature.

MICHAEL JOSEPH McANDREW.
